LOUIS J. FEDDER, OF OWATONNA, MINNESOTA, ASSIGNOR TO KING VENTILATING COMPANY, OF OWATONNA, MINNESOTA, A CORPORATION OF MINNESOTA.

DRIVING MECHANISM FOR FANS.

Application filed November 28, 1924. Serial No. 752,700.

This invention relates particularly to driving mechanism for ventilator fans of the type adapted to be mounted upon the ceilings of creameries or other buildings where it is desirable to withdraw foul air, steam or gases.

It is my object to provide simple mechanism of this kind which is more compact and silent than the mechanism heretofore used for this purpose and at the same time to facilitate proper alignment of a pulley of the mechanism with a pulley on a main drive shaft.

Heretofore it has been common practice to drive the vertical fan shaft of such mechanism by attaching a pulley to the lower end thereof and to obtain the required speed ratio by interposing a horizontal counter shaft between the fan shaft and main drive shaft, the latter shafts being journaled in brackets attached to the ceiling. In this class of ventilators, belts, one of which must be twisted, are utilized to connect the several shafts. Obviously, this old arrangement of shafts severally driven by belts occupies a comparatively large amount of space and is not durable because the twisted belt requires a flanged pulley on the fan shaft which causes rapid wear upon the belt. Old types of driving mechanisms have the further disadvantage of requiring accurate alignment of the driving pulleys at the time when the fan frames are attached to the ceilings. By the present invention, I obviate these defects.

In the accompanying drawings I have illustrated the best form of my device at present known to me. Referring to the drawings, Figure 1 is a central vertical section of my improved driving mechanism mounted upon a ceiling; Fig. 2 is a bottom plan view of the same; Fig. 3 is a detail of the gearing and shaft casing with the cover removed and Fig. 4 is a fragmentary side elevation showing the pulleys and belt shifting mechanism.

As shown in the drawings, the frame of my device has a ring 5 adapted to be secured by bolts 6 to a ceiling 7. An annular receptacle 8 formed on the inner periphery of the ring 5 is arranged to receive the lower end of a flue 9 through which the exhaust from the fan is forced. Secured by bolts 10 to the ring 5 is a spider 11 adapted to support a casing 12 for a vertical shaft 13.

A hub 14 fast on the upper end of the shaft 13 is arranged to carry a series of fan blades 15. These fan blades 15 are reinforced and maintained in proper position by radial bars 16 fixed in the hub 14 and a hoop 17 connecting the outer ends of the blades.

The casing 12 extends through a central aperture 18 in the spider 11 and is formed with an annular flange 19 fitting in a recess about said aperture. To adjustably hold the flange 19, the spider 11 is pierced by a series of bolts 20 which carry stout washers 21 on their lower ends. The washers 21 overlap the bottom of the flange 19 so that the nuts on the lower ends of the bolts 20 may be manipulated to grip or release said flange.

Journaled in projecting portions 22 and 23 of the casing 12 is a horizontal shaft 24, 75 operatively connected to the vertical shaft 13 by spiral gears 25 and 26. The casing 12 has an enlarged portion 27 containing the spiral gears and is provided with a removable cover 28. An end of the shaft 24 projects from the portion 22 of the casing and has a fixed pulley 29 and a freely revoluble pulley 30 mounted thereon. A belt 31 is movable from one of the pulleys to the other by means of guide fingers 32 fixed on an end of a slid able rod 33. This rod 33 is supported in a pair of arms 34 extending obliquely downward from the portions 22 and 23 of the casing 12. Suitable set screws are provided to secure the arms upon the casing, and cords or ropes 35 and 36 are attached to the rod 33 and pass through rings 37 in the arms 34, being arranged to be manipulated to shift the belt 31 from one to the other of the pulleys 29 and 30. 95

In operation the belt 31 is driven by a pulley on the main drive shaft (not shown) and the fan is started by manipulating the cord 36 to move the belt to the pulley 29. This, as will be readily understood, rotates the vertical shaft 13 carrying the fan blades 15 through the spiral gears 25 and 26. These gears are preferably arranged to drive the shaft 13 at twice the speed of the shaft 24. By my arrangement of spiral gears in a closed casing I make it possible to operate the gears packed or immersed in a heavy lubricant and thus obtain an unusually silent driving mechanism.

An important feature of the present in- 110

vention is the provision for easy and accurate alignment of the pulleys 29 and 30 with the pulley on the main drive shaft. Thus, after the ring 5, flue 9, and spider 11 have been installed in a building, the nuts on the bolts 20 may be loosened to allow rotation of the casing 12, together with its contents and the pulleys 29 and 30.

Having described my invention what I claim as new and desire to protect by Letters Patent is:

1. The combination in a ventilator having a vertical shaft and a fan mounted on the upper end of said shaft, of a frame adapted to be attached to the ceiling of a room to be ventilated, a casing for said shaft arranged to be pivoted horizontally on said frame, a horizontal shaft extending into said casing and operatively connected with said vertical shaft therein, a drive wheel on said horizontal shaft, and means for securing said casing against pivotal movement on said frame.
2. The combination in a ventilator having a vertical shaft and a fan mounted on the upper end of said shaft, of a casing pivoted for horizontal turning on the lower end of said shaft, a horizontal shaft journalled in said casing and operatively connected with said vertical shaft therein, and means for securing said casing against pivotal movement on said vertical shaft.
3. The combination in a ventilator having a vertical shaft and a fan mounted on the upper end of said shaft, of a frame adapted to be secured to the ceiling of a room to be ventilated, a casing on the lower end of said shaft formed with an annular flange which

is pivoted for horizontal rotation on said frame, means for securing said flange against rotation on said frame, a horizontal shaft journalled in said casing, spiral gears operatively connecting said horizontal and vertical shafts in said casing, and a drive wheel on said horizontal shaft.

4. In driving mechanism for a ventilating fan, a spider having a series of arms adapted to be attached at their outer ends to a supporting surface, a shaft bearing mounted centrally in said spider, a shaft journalled in said bearing and arranged to drive a fan at one side of said spider, a second shaft operatively connected with said first mentioned shaft on the other side of said spider, means for supporting said second shaft on said spider and a drive pulley fixed on said second shaft.

5. In driving mechanism for a ventilator fan, a spider having a series of arms adapted to be attached at their outer ends to a supporting surface, a shaft bearing pivotally mounted centrally in said spider, an annular flange on said bearing, means for adjustably clamping said flange on said spider, a shaft journalled in said bearing and arranged to drive a fan at one side of said spider, a gear housing supported on said flange at the other side of said spider, a second shaft journalled in said housing, gearing operatively connecting said first and second mentioned shafts in said housing, and a drive pulley fixed on a projecting end of said second shaft.

In testimony whereof, I have hereunto signed my name to this specification.

LOUIS J. FEDDER.
